UNITED STATES PATENT OFFICE.

CHARLES HENRY AUGUSTUS FREDERICK LOCKHART ROSS, OF BALNAGOWN CASTLE,
COUNTY OF ROSS, SCOTLAND.

MUSHROOMING BULLETS.

1,141,212.

Specification of Letters Patent. Patented June 1, 1915.

Application filed February 13, 1915. Serial No. 8,102.

To all whom it may concern:

Be it known that I, CHARLES HENRY AUGUSTUS FREDERICK LOCKHART Ross, a subject of the King of Great Britain, residing at Balnagown Castle, Rossshire, Scotland, have invented certain new and useful Improvements in Mushrooming Bullets; and I do hereby declare the following to be a full, clear, and exact description of the invention, such as will enable others skilled in the art to which it appertains to make and use the same.

This invention relates to jacketed bullets, for sporting purposes, and has for its object to improve the construction of the bullet disclosed in the U. S. Patent No. 949,028, dated February 15, 1910, and entitled "Bullets".

To these ends the invention consists in the novel details of construction and combinations of parts more fully hereinafter disclosed and particularly pointed out in the claims.

Referring to the accompanying drawings forming a part of this specification, in which like numerals designate like parts in all the views:—Figure 1 is a plan view partly in section of a bullet made in accordance with the present invention; Fig. 2 is a view similar to Fig. 1, but showing a slightly modified form of mushrooming tube; Fig. 3 is a sectional view of the mushrooming tube removed from the bullet, shown in Fig. 1; Fig. 4 is a like view of the mushrooming tube shown in Fig. 2; Fig. 5 is a diagrammatic view in section, illustrating how the mushrooming tubes are first drawn; Fig. 6 is a diagrammatic view in section illustrating how said mushrooming tubes are later closed by die hammer blows; and Fig. 7 is a diagrammatic view in section of a bullet provided with a mushrooming tube in accordance with U. S. Patent No. 949,028 above mentioned, and showing the defects therein greatly exaggerated.

1 indicates the original jacket of a bullet provided with the usual filling material 2, and 3 illustrates a mushrooming tube placed in the pointed end of the bullet having a closed end 4 and a pointed closed end 5, all as will be clear from the drawings.

In the prior U. S. Patent No. 949,028 above, the inner end 4 of the tube 3 was left open as indicated at 6, in Fig. 7, and the pointed head 7 was closed, as will be clear from the said patent and the said figure.

In order to render clear the difference between the present invention and that of the prior patent above, it is said:—The tubes 3 were drawn in dies as illustrated in Fig. 5, leaving a bottom, such as 4 integral therewith, and the said bottom 4 was put into a suitable die shaping apparatus having hammers 8 (see Fig. 6), whereupon the said hammers 8 delivered a multitudinous number of light hammer blows upon the closed end 4 of the tube. These blows cause the head 4 of the tube 3 to assume the particular shape shown in Fig. 7. It was found however after considerable experience in actual use that the bullets thus shaped did not always mushroom with uniformity, nor were they under all circumstances sufficiently accurate in flight to warrant complete satisfaction, to the user. After a series of experiments, extending over a considerable time, the cause of these objections were found to reside in the fact that the bottom 4 of the tubes 3 were always more or less thickened over the walls of the tube as is indicated by 9. This thickening of the bottoms 4 is an unavoidable incident due to the drawing operation, because the metal of necessity flows more uniformly and freely along the walls of the tube where the pressure is greatest than it does along the bottom of the tube. Further, the tubes 80 of necessity being quite small and the walls thereof of necessity being quite thin, the above thickening of the bottoms 4 is not as apparent as it would otherwise be. Upon careful calibration of the bottom and walls 85 of a large number of tubes I have found that the bottoms of the tubes are not only often several times thicker than are the walls of the tubes, but that this thickness of the bottoms causes the hammer blows 8 on said bottoms 4 to so shape the ends 7 of the tubes 3 that the walls of the said ends have varying degrees of thickness as indicated at 11 and 12 in Fig. 7. These varying degrees of thickness of course cause the head 7 to lack 100 uniformity in their mushrooming actions, and therefore to give rise to the above objections to the bullets disclosed in said Patent No. 949,028.

Now this invention avoids the above objections by placing the thickened bottoms 4 of the tubes 3 inside the bullet body, instead of outside thereof, as will be clear from Figs. 1 and 2, and by causing the blows of the hammers 8 to close the outer walls of the 110

tubes which have a uniform thickness as will be clear from Fig. 6. In other words, by placing the bottoms 4 inside the bullets and closing the open ends of the tubes as indicated, the said mushrooming tubes 3 are provided with heads 5 having absolutely uniform thickness of walls and therefore they have absolutely a uniform mushrooming action under all conditions.

10 The importance of this result will be apparent when it is said that with modern high powdered bullets any unevenness in the outer contour or shape of the bullet causes considerable deviation or inaccuracy over long flights and therefore it is of the utmost importance to not only have a uniform and accurate outer contour, but in mushrooming bullets it is of equal importance to have a uniform mushrooming action, because if a bullet mushrooms while in flight, of course its accuracy is at once destroyed. The same is true if the head 5 or 7 of the tube is injured in packing or in loading.

15 In the modified form of my invention disclosed in Figs. 2 and 4 the extreme end 15 of the tube 3 is substantially closed but not closed to the same extent as are the extreme ends of the tubes shown in Figs. 1 and 3. Or if the said end 15 is in fact closed it is 20 left blunt as indicated to facilitate the mushrooming action. Accordingly it will be observed that by the simple expedient of placing the closed end 4 of the tube 3 inside the bullet instead of outside thereof, and by 25 closing or substantially closing by hammer blows the open end of the tube to form the

sharp pointed head 5, I not only provide a novel construction of mushrooming tube, but also a bullet which is more certain in its action than the similar bullets heretofore proposed.

30 It is obvious that those skilled in the art may vary the details of construction as well as the arrangement of parts without departing from the spirit of my invention, and therefore I do not wish to be limited to the above disclosure except as may be required by the claims.

What I claim is:—

1. A sharp nosed bullet comprising a 35 mushrooming tube having a pointed outer end composed of a wall of uniform thickness formed by closing the open end of the tube and provided with an integral bottom located in the body of the bullet, substantially as described.

2. A sharp nosed bullet comprising a mushrooming tube having a pointed outer end composed of a wall of uniform thickness formed by closing the open end of the tube 40 and conforming to the outer contour of the nose of the bullet said tube being provided with an integral bottom located in the body of the bullet, substantially as described.

35 In testimony whereof I affix my signature, in presence of two witnesses.

CHARLES HENRY AUGUSTUS
FREDERICK LOCKHART ROSS.
